UNITED STATES PATENT OFFICE.

HARRY BREWERTON DUANE, OF BROOKLINE, MASSACHUSETTS, ASSIGNOR TO THE TOURNAINE COMPANY, OF BOSTON, MASSACHUSETTS, A CORPORATION OF MASSACHUSETTS.

DESIGN FOR A WRAPPING-BAND OR ARTICLE OF SIMILAR NATURE.

54,836.

Specification for Design.

Patented Apr. 13, 1920.

Application filed June 10, 1919. Serial No. 303,237. Term of patent 14 years.

To all whom it may concern:

Be it known that I, HARRY BREWERTON DUANE, a citizen of the United States, residing at Brookline, in the county of Norfolk and State of Massachusetts, have invented a new, original, and ornamental Design for a Wrapping-Band or Article of Similar Nature, as shown in the accompanying drawing and described in the following specification.

The drawing is a plan view of the wrapping band showing my new design.

The design comprises a ribbon-like sheet or strip 2, having at a suitable location thereon an acorn-shaped medallion 3, the upper and lower portions 4 and 5 of which extend beyond the side lines of the strip or body 2, and the sides of the acorn-like figure being extended transversely across the strip as at 6—6.

I claim:

The ornamental design for a wrapping band or article of similar nature as shown and described.

HARRY BREWERTON DUANE.
